TOOTHBRAHSH

Herbert M. Graham, Sacramento, Calif.

Application April 19, 1956, Serial No. 579,218

8 Claims. (Cl. 15—129)

This invention relates to oral hygiene devices and particularly to a toothbrush and holder combination which selectively delivers water and an additive such as toothpaste, to the mouth of the user.

An object of the invention is to provide a practical toothbrush and holder combination which is capable of being produced by practical manufacturing methods in a small, lightweight condition, the device being arranged to deliver at the option of the user liquid under pressure through the head of the toothbrush or liquid mixed with an additive which may be selected by the user.

It is understood that tooth cleaning appliances of the fountain brush type have been constructed in the past. Accordingly, it is a further object of the invention to provide an improved fountain type toothbrush where the control for the passage of liquid through the toothbrush is most accessible to the user, it being located immediately below one or more of the fingers of the user when the device is held in the hand. Mere squeezing of the holder opens the normally closed valve to admit water into the passage of the holder and passageway of the removably carried toothbrush in the holder.

A further object of the invention is to provide a combination toothbrush and holder wherein the toothbrush is easily separated from the holder and securely locked in the holder by a novel latch construction, the latter being openable by rotating a single lever several degrees and closed by rotating the same lever the same distance in the opposite direction.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a perspective view of a part of a room wherein a typical sink is located, an embodiment of the invention being mounted operatively in connection with it;

Figure 2 is a longitudinal sectional view of the teeth cleaning device which exemplifies the principles of the invention;

Figure 3 is an elevational side view of the device in Figure 2;

Figure 4 is a side view of the holder for the toothbrush, some parts being shown in section and illustrating particularly the condition of the latch when the toothbrush is capable of being inserted or removed from the holder;

Figure 5 is a side view of a toothbrush adapted to be held by the holder, parts of the toothbrush being shown in section;

Figure 6 is an elevational front view of the device in Figure 3;

Figure 7 is an elevational back view of the device of Figure 6;

2

Figure 8 is a transverse sectional view taken on the line 8—8 of Figure 2; and

Figure 9 is a perspective view of a part of the valve for the control of water through the holder and toothbrush for ultimate emission into the mouth of the user.

In Figure 1 there is a sink 10 mounted on wall 12, the sink having controls 14 and 16 which are used to select the temperature of water mixture which passes through the outlet pipe 16 and into the sink 10. This is but one type of many presently available arrangements for water under pressure. Accordingly the sink with its controls and water outlet pipe 16 is intended to be a schematic representation of any standard plumbing fixture capable of serving as a water supply for the water line 18. This water line has means at one end for detachably connecting to the water outlet pipe 16. For example the means may assume the form of a bell 20 of suitable, flexible material, for example rubber. The bell is frictionally fitted over the end of pipe 16 so that the water line 18 is supplied with water under pressure depending on the setting of the controls 14 or 16. As a companion to the water line 18 there is a conductor 22, the latter being secured to the line 18 for a considerable part of the length of the line for convenience. It is preferred although not essential, that both line 18 and conductor 22 be made of flexible tubing. The function of conductor 22 is to supply an additive to the device 24 while the function of line 18 is to supply water under pressure thereinto. Therefore, a manually operable pump is in container 26 and is adapted to be operated by depression of handle 28. Container 26 has a supply of an additive for the liquid which passes through the teeth cleaning device 24. This additive may be liquid toothpaste, powder toothpaste or other liquid or powder such as a medicament or cosmetic preparation. Mounting bracket 30 is on wall 12 and has means detachably securing the container 26 to it.

The teeth cleaning device 24 consists of holder 32 and brush 34. The brush is of approximately standard form having a handle 38 together with a head 40 at one end of it. The head has tufts of bristles between which there are orifices 42 that are in registry with a water manifold 44 in the head of the brush. This manifold consists of the outer end of the liquid passageway 46 which extends completely through the longitudinal handle 38 and into the head 40 of the brush. The outer end of handle 38 is preferably smoothly curved as at 47 (Figure 5) in order to seat well on the yielding seat 48 that is located in holder 32.

Holder 32 comprises a body 50 that has a sleeve 52 protruding therefrom and fitting around a part of body 50. The U-shaped end 54 of sleeve 52 is juxtaposed over three sides of the body 50. Cover 56 is disposed over portions of two of the sides of the body 50 and the fourth side thereof. The cover 56 is shaped to fit neatly in the hand of the user and has a pair of bolts 58 which holds it fastened to body 50. Handle 38 of the toothbrush is located in bore of sleeve 52, the dimensioning of the handle and the bore being such that the handle fits snugly therein. When pressed gently into the bore of sleeve 52 the curved end 47 of the handle 38 presses on the flexible, for example rubber, seat 48. Seat 48 has an aperture in it which is in registry with the passageway 46. A longitudinal passage 60 is formed in body 50 and is in communication with the aperture in seat 48 and also in alignment with the passageway 46 when the toothbrush is latched in place in holder 32. The means for releasably latching the toothbrush in the holder must be quickly and easily operable. Accordingly, the toothbrush handle 38 is formed with a notch 62 intermediate its ends, this notch having an angular wall 64 at one end. A latch keeper, preferably in the form

of a small plate 66 and having an angulated end wall 67, is adapted to be pressed into the notch 62 in order to hold the toothbrush firmly in place. When in the latched condition the angulated walls 64 and 67 are nested with each other (Figure 2). A lever 68 is pivoted on a pin 70 to the exterior of sleeve 52 near the opening 72 therein. This pin is mounted in ears that are carried by the sleeve 52, whereby the lever 68 is capable of swinging movement toward and away from the holder 32. A link, for example a U-shaped lightweight, wire 74 is pivoted at one end to the lever 68 and pivoted at the opposite ends to the keeper 66. When the lever 68 is swung outwardly to the position shown in Figure 4 the keeper plate 66 slides outwardly from beneath a part of sleeve 52 and from within the notch 62. When the lever 68 is swung in the opposite direction the keeper plate 66 is swung inwardly and downwardly fitting in the small pocket (Figure 2) 75 which is formed by wall 64 of notch 62, a part of the innermost wall of notch 62 and the inner surface of a part of the sleeve 52.

A valve 78 is carried by the holder 32 and constitutes a part thereof. The valve consists of a stem 79 having a threaded end 80 on which the valve element 82 is threaded. Stem 79 is operable in a bore 83 which is arranged generally parallel to the passage 60. Spring 84 holds the valve 78 in the normally closed position and is disposed in a counterbore 85, the counterbore being in alignment with bore 83. This spring seats upon the end of counterbore 85 and on a sliding block 86 to which the outer end of stem 79 is secured. A pilot rod 88 is fixed to an offset part of the sliding block 86 and is operable in a passage 87 parallel to bore 83. Aperture 90 is formed in sliding block 86 in order to connect links 91 and 92 thereto by means of a pivot pin. The outer ends of links 91 and 92 are pivoted to link 93, the latter being mounted for pivotal movement on pin 94 that is carried by brackets on the outer surface of sleeve 52 near the opening 72 in this sleeve.

A valve chamber 96 is formed in the body 50 and has the valve 78 operable therein. This valve chamber has a valve seat 97 in it between its ends, one end of the valve chamber being in registry with the passage 60 so that the valve 78 controls the flow through passage 60. Coupling 98 is threaded on a part of the body 50 at valve chamber 98, this coupling having water line 18 attached to it for operative connection with holder 32.

The conductor 22 has an end fitted over the nipple 100, the latter being part of a right angular coupling 102 in which there is a normally closed check valve 104. This right angle connector is threaded in the body 50 and has its passage in registry with the lower end of passage 60.

In use the device is held in the hand with holder 32 arranged such that the link 93 is beneath at least one of the user's fingers. With the other hand the user depresses pump actuator knob 28 so that a charge of liquid or powder passes through the conductor 22, check valve 104 and into passage 60 where it is mixed with the water flowing into the head of the toothbrush. After experiencing the device the prerogative of the user will be exercised in how to administer oral hygienic treatment to himself. Inherent in the described embodiment of the invention is sufficient versatility for performing a number of approved functions in oral and dental hygiene.

In order to remove the toothbrush for one reason or another, the actuation of lever 68 from the position shown in Figure 2 to the position shown in Figure 4 is all that is necessary. Then the toothbrush is capable of being easily slid from sleeve 42 for either cleansing or replacement. To replace the toothbrush it is slipped into the sleeve 52 and the lever 68 returned from the position shown in Figure 4 to the position shown in Figure 2. This automatically brings the keeper plate 66 into engagement with notch 62.

The foregoing is considered as illustrative only of the

principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention as claimed.

What is claimed as new is as follows:

1. In a teeth cleaning device, a toothbrush having a handle provided with a passageway which opens adjacent to the bristles thereof, a holder for said brush handle and including a sleeve in which said handle is separately disposed, said sleeve having an opening in one wall, a keeper sized for reception in said opening, said handle having a notch in which said keeper is adapted to lock, a lever pivoted to said sleeve near said opening, a link extending through said opening and pivoted to said lever and said keeper to move said keeper in response to movement of said lever, a passage in said holder communicating with said passageway, a water line, a valve chamber connecting said passage with said water line, and a manually operable and normally closed valve in said valve chamber.

2. In a teeth cleaning device, a toothbrush having a handle provided with a passageway which opens adjacent to the bristles thereof, a holder for said brush handle and including a sleeve in which said handle is separately disposed, said sleeve having an opening in one wall, a keeper sized for reception in said opening, said handle having a notch in which said keeper is adapted to lock, a lever pivoted to said sleeve near said opening, a link extending through said opening and pivoted to said lever and said keeper to move said keeper in response to movement of said lever, a passage in said holder communicating with said passageway, a water line, a valve chamber connecting said passageway with said water line, a manually operable and normally closed valve in said valve chamber, and means including a linkage connected to said valve and said holder for opening said valve.

3. In a teeth cleaning device, a toothbrush having a handle provided with a passageway which opens adjacent to the bristles thereof, a holder for said brush handle and including a sleeve in which said handle is separately disposed, said sleeve having an opening in one wall, a keeper sized for reception in said opening, said handle having a notch in which said keeper is adapted to lock, a lever pivoted to said sleeve near said opening, a link extending through said opening and pivoted to said lever and said keeper to move said keeper in response to movement of said lever, a passage in said holder communicating with said passageway, a water line, a valve chamber connecting said passageway with said water line, a manually operable and normally closed valve in said valve chamber, means including a linkage connected to said valve and said holder for opening said valve, a pump, and a conductor extending from said pump to said passage to deliver an additive to said passage.

4. The device of claim 3 wherein said conductor and said water line comprise at least in part a pair of flexible tubes.

5. In combination, a toothbrush having a handle and a head, a passageway extending through said handle and opening at said head adjacent to the bristles thereon, a holder for said toothbrush handle and comprising a body, a sleeve connected with said body and accommodating said handle of said toothbrush, said sleeve and body having a passage which is in registry with said passageway in said handle when said handle is located in said sleeve, means to latch said toothbrush handle in said sleeve and including a latch keeper, means for displacing said latch keeper, said toothbrush handle having a notch in which to accommodate said latch keeper, a valve carried by said body, means depressible by the same hand which holds the holder for opening said valve, means operatively associated with said body for holding a fluid line in communication with said valve so that said

valve controls the passage of fluid into said body, said valve being in registry with said passage, and means for introducing an additive to the fluid downstream of said valve.

6. In combination, a toothbrush having a handle and a head, a passageway extending through said handle and opening at said head adjacent to the bristles thereon, a holder for said toothbrush handle and comprising a body, a sleeve connected with said body and accommodating said handle of said toothbrush, said sleeve and body having a passage which is in registry with said passageway in said handle when said handle is located in said sleeve, means to latch said toothbrush handle in said sleeve and including a latch keeper, means for displacing said latch keeper, said toothbrush handle having a notch in which to accommodate said latch keeper, a valve carried by said body, means depressible by the same hand which holds the holder for opening said valve, means operatively associated with said body for holding a fluid line in communication with said valve so that said valve controls the passage of fluid into said body, said valve being in registry with said passage, means for introducing an additive to the fluid downstream of said valve, said additive introducing means including a conductor, means for issuing the additive under pressure through said conductor, a check valve in said conductor, and a passage-

10

15

20

25

way extending from said check valve into said passage.

7. The combination of claim 6 wherein said valve opening means includes a hand movable link, a pair of links operatively connected to the first mentioned link, a valve stem, a sliding member to which said pair of links are pivoted and to which said valve stem is attached, and a spring reacting on said body and said sliding member normally holding said valve in the closed position.

8. The combination of claim 7 wherein said sliding member has a pilot rod secured to it and said body has a passage in which said pilot rod is slidible.
